Specification for Design.

Patented July 20, 1920.

Application filed April 10, 1919. Serial No. 289,142. Term of patent 14 years.

To all whom it may concern:

Be it known that I, MATTHEW B. MUXEN, a citizen of the United States, residing at Fort Wayne, in the county of Allen and State of Indiana, have invented a new, original, and ornamental Design for a Casing for a Dispensing Apparatus, of which the following is a specification, reference being had to the accompanying drawing, forming part thereof.

The figure is a perspective view of a cas-

ing for a dispensing apparatus, showing my new design.

I claim:

The ornamental design for a casing for a dispensing apparatus as shown.

In testimony whereof I affix my signature, in presence of two witnesses.

MATTHEW B. MUXEN.
